FIG. 1

FIG. 2

FIG. 3

INVENTOR

Albert H. Neller.
William Louden.
ATTORNEY

UNITED STATES PATENT OFFICE.

ALBERT H. NELLER, OF FAIRFIELD, IOWA, ASSIGNOR TO THE LOUDEN MACHINERY COMPANY, OF FAIRFIELD, IOWA, A CORPORATION OF IOWA.

OVERHEAD-TRACK HANGER.

1,349,141.

Specification of Letters Patent. Patented Aug. 10, 1920.

Application filed June 12, 1920. Serial No. 388,445.

To all whom it may concern:

Be it known that I, ALBERT H. NELLER, a citizen of the United States, residing at Fairfield, county of Jefferson, and State of 5 Iowa, have invented a new and useful Improvement in Overhead-Track Hangers, of which the following is a specification.

My invention relates to means for suspending overhead tracks in position for elevated carriers to run upon, and it consists 10 of an improved form of a suspending member and a clamping member, both made of strips of rolled metal pressed into shape and clamped together so as to securely grip and 15 hold the head of a track-rail between their lower ends, the suspending member being adapted to connect with an overhead support, and the clamping member being securely held in place on the suspending member. 20 Also, the members being mutually adjusted to avoid interference with the wheels of the carrier, all of which is hereinafter particularly set forth and duly specified in the claims.

25 In the accompanying drawings forming a part of this specification, Figure 1 is a side view of a track-hanger and a short section of track-rail embodying my invention. Fig. 2 is a vertical transverse section on line 2—2 of Fig. 1, showing a pair of carrier wheels mounted on the wheel supporting flanges of the track-rail. Fig. 3 is a horizontal section on line 3—3 of Fig. 1.

Referring to the drawing. A represents 30 a short section of track-rail and B the suspending member, which is provided with an opening C in its upper end to receive a supporting hook or bracket, which being well known in the art, is not shown in the drawing. D represents the clamping member 35 which is held in engagement with the suspending member by means of a bolt E having a bur F. The lower ends of the members B and D are spread apart and then turned to catch around and under the upper 40 bead or head G of the track-rail A.

The member B is fitted with an opening H a little below the upper end of the member D and a portion of the latter member 45 opposite this opening is cut away at its lower edge and is bent to the side so as to form a projecting integral lug I which is adapted to enter the opening H and rest on its lower edge, thus forming an additional 55 support besides the bolt E to hold the mem-

ber D more securely in place on the member B, and to prevent it from slipping downward if the bur F on the bolt E should not be drawn sufficiently tight, or the hole through which it passes should be a little too 60 large for the bolt.

In Fig. 2, J represents a pair of carrier wheels adapted to run on the outer portions of the wheel supporting flanges K of the track-rail A. In order that these wheels 65 may be permitted to run freely along the track and not meet with obstructions it is advantageous that the parts of the track-hanger between the wheels be located as nearly in the center as possible, so that none 70 of its parts will project farther out from the center of the track on one side than on the other.

When bolts are used to hold the hanger members together, the burs being larger and 75 more angular than the heads of the bolts, it is advisable that the burs be set closer to the center of the track than the heads, in order that the spaces between them and the carrier wheels be substantially the same as 80 the spaces at the heads of the bolts. To accomplish this result I have dished one of the members into the other where the bolt passes through them. To be more particular, I have dished the member D in toward 85 the center line of the track and the member B out from said center at this point.

By this means more space is secured for the burs than is needed for the heads of the bolts, and the free spaces between them and 90 the carrier wheels will be substantially equal. If there is any difference the burs being more angular than the heads of the bolts, the spaces between the burs and the carrier wheels should be more than the 95 spaces between the wheels and the rounded heads of the bolts, which greater spaces may be secured by dishing one of the hanger members into the other at the points where the bolts pass through them, as already explained and as shown in the drawings.

It is evident that the opening H may be placed in the clamping member D and the integral lug I may be formed on the suspending member B and be adapted to enter 105 the opening in the clamping member to assist in supporting it without departing from the spirit of my invention. When this is done the lug being on the suspending member will come in contact with the upper edge 110

of the opening in the clamping member to support it in position as will be readily understood by those skilled in the art. In this event it may be preferable to cut away 5 the material forming the integral lug on its upper side instead of on the lower side as shown in the drawing.

What I claim is:

1. In hangers for overhead tracks, a suspending member having means to connect with an overhead support, a shorter clamping member adapted to be connected to the suspending member, both members being made of rolled metal pressed to shape and having their lower ends spread apart and inturned to catch around and under the head of a track-rail, an opening in the body of the suspending member below the upper edge of the clamping member, and a portion 20 of the clamping member being cut away at its lower edge opposite the opening in the suspending member and bent to the side to form an integral laterally projecting lug to enter the opening in the suspending member and to rest upon the lower edge of the opening, thus forming a support for the clamping member.

2. In hangers for overhead tracks, a suspending member having means to connect 30 with an overhead support, a shorter clamping member adapted to be connected to the suspending member, both members being made of rolled metal pressed to shape and having their lower ends spread apart and inturned to catch around and under the head of a track-rail, an opening in the body of the suspending member below the upper edge of the clamping member, a portion of 35 the clamping member being cut away at its lower edge opposite the opening in the suspending member and bent to the side to form an integral laterally projecting lug to enter the opening in the suspending member and to rest upon the lower edge of the opening, 40 thus forming a support for the clamping member, and a bolt to hold the members together.

3. In a device of the character described, a suspending member having means to connect 50 with an overhead support, a shorter clamping member adapted to be connected to the suspending member, both members being made of rolled metal pressed to shape and having their lower ends spread apart 55 and inturned to catch around and under the

head of a track-rail, and a bolt to hold the members together, the portions of the members where the bolt passes through them being dished, one into the other, substantially as and for the purpose specified.

4. In a device of the character described, a suspending member having means to connect with an overhead support, a shorter clamping member adapted to be connected to the suspending member, both members 60 being made of rolled metal pressed to shape and having their lower ends spread apart and inturned to catch around and under the head of a track-rail, and a bolt to hold the members together, the portions of the members where the bolt passes through them being dished, one in toward the center line 65 of the track-rail and the other out from said center line, substantially as, and for the purpose set forth.

5. In a device of the character described, a suspending member having means to connect with an overhead support, a shorter clamping member adapted to be connected to the suspending member, both members 70 being made of rolled metal pressed to shape and having their lower ends spread apart and inturned to catch around and under the head of a track-rail, and a bolt to hold the members together, the clamping member 75 being dished in toward the center line of the track-rail where the bolt passes through it, and the suspending member being dished out from said line at this point, substantially as shown and described.

6. In hangers for overhead tracks, a suspending member having means to connect with an overhead support, a shorter clamping member adapted to be connected to the suspending member, both members being 80 made of rolled metal pressed to shape and having their lower ends spread apart and inturned to catch around and under the head of a track-rail, an opening in the body of one of the members, and an adjoining portion 85 of the other member being cut away at one edge and bent to the side to form an integral laterally projecting lug to enter the opening in the other member, whereby the lug will form a support for the clamping 90 member, and means to hold the members together.

Fairfield, Iowa, June 10th, 1920.

ALBERT H. NELLER.
